A. GOERTZ

LOCKING OR HOLDING CATCH

Filed March 30, 1923

INVENTOR:
August Goertz,
BY
Fraenzel and Richards
ATTORNEYS.

UNITED STATES PATENT OFFICE.

AUGUST GOERTZ, OF NEWARK, NEW JERSEY, ASSIGNOR TO AUGUST GOERTZ & CO., OF NEWARK, NEW JERSEY, A CORPORATION OF NEW JERSEY.

LOCKING OR HOLDING CATCH.

Application filed March 30, 1923. Serial No. 628,711.

To all whom it may concern:

Be it known that I, AUGUST GOERTZ, a citizen of the United States, residing at Newark, in the county of Essex and State of New Jersey, have invented certain new and useful Improvements in Locking or Holding Catches; and I do hereby declare the following to be a full, clear, and exact description of the invention, such as will 10 enable others skilled in the art to which its appertains to make and use the same, reference being had to the accompanying drawings, and to characters of reference marked thereon, which form a part of this 15 specification.

This invention relates, generally, to improvements in catches; and, the present invention has reference, more particularly, to a novel and simply constructed locking 20 or holding catch which is especially adapted for use with portfolios, pocket-books, bags, suit-cases, and the like.

The present invention has for its principal object to provide a novel and simply 25 constructed locking or holding catch of the general character hereinafter set forth, in which the various parts are reduced to a minimum, which is neat and ornamental in appearance, and is most effective in its 30 operation.

Other objects of the invention not at this time more particularly enumerated will be clearly understood from the following detailed description of the same.

With the various objects of the present invention in view, the said invention consists, primarily, in the novel locking or holding catch hereinafter more fully set forth; and, the invention consists, furthermore, in the novel arrangements and combinations of the various devices and parts, as well as in the details of the construction of the said parts, all of which will be more fully described in the following specification, 45 and then finally embodied in the clauses of the claims which are appended to and which form an essential part of the said specification.

The invention is clearly illustrated in the drawings, in which:—

Figure 1 is a front face view of a locking or holding catch showing one embodiment

ment of the principles of the present invention, and illustrating the separable members of the catch secured to the separable members of a portfolio, or other suitable receptacle, as a bag, vanity-case, suit-case, or the like; and Figure 2 is a side elevation of the said locking or holding catch with the members which are to be locked by means of the catch being shown in their closed and locked relation.

Figure 3 is a side elevation of the said locking or holding catch, the members thereof being represented in their separated or unlocked relation.

Figure 4 is a rear face view of the locking or holding catch, the various parts thereof being represented in their engaged or locked relation.

Figures 5 and 6 are perspective views, showing collectively but in their disengaged relation the main members or elements of the catch, Figure 5 representing the front face-portions of the catch, and Figure 6 the rear face-portions of the same, and Figure 7 is a perspective view of the hasp-member of the catch.

Similar characters of reference are employed in all of the said above described views, to indicate corresponding parts.

Referring now to the several figures of the drawings, the reference-characters 1 and 2 indicate fragmentary portions of two members of a port-folio, music-roll, pocket-book, bag, vanity-case, suit case, or the like, which are to be brought into locked relation by means of the holding or locking catch.

The holding or locking catch which embodies the principles of the present invention comprises two box-like elements or shells, as 3 and 4; the lower element 3 being adapted to be secured to the member 1 by means of fastening lugs 5, or other suitable fastening means, and the upper element 4 being adapted to be secured to the member 2 by means of fastening lugs 6, or other suitable fastening means.

The said lower element 3 which may be of any suitable configuration, but which is preferably of a rectangular configuration, as here shown, is made in the form of a chambered shell or box, the face-plate of which is surrounded by the marginal flanges or edges 7.

Connecting the side flanges or edges of the said chambered shell or box is a vertical wall, as 8, which is provided with a lug-receiving opening, as 9.

- 5 The upper element 4, herein-above mentioned, may also be of any suitable configuration, preferably of the rectangular configuration here shown, and the same is made in the form of a chambered shell or box, the 10 face-plate of which is surrounded by the marginal flanges or edges 10. The said side edges or flanges 10 are cut away or slotted, as at 11, and are also formed with the outwardly curved portions or horns 12, the said 15 slotted portions 11 providing suitable bearings in which the cross-bar or member 14 of of the hasp-member 13 is oscillatorily disposed, and the said outwardly curved portions or horns 12 serving as stops adapted to 20 engage with the lower curved surface-portions 15 of the side-members of the hasp to properly support the hasp in its lowered position, as will be evident. The connecting member 16 of the hasp may be provided with 25 a suitably formed fingerpiece, as 17, for raising and lowering the hasp from and into its locking or holding relation with sides of the lower chambered shell or box 3.
- 30 Near the bearings formed by the herein-above mentioned slotted portions 11, the upper shell or box 4 is provided with laterally extending flanged portions, as 18, the connecting portion located between said flanged portions 18 being provided with a 35 downwardly extending lock-stud or lug 19, surrounded upon its back by a marginal flange 20. Within the back or chamber of the said upper shell or box 4 is a resilient spring-plate 21, extending beneath a cam-member 22 extending angularly from the cross-bar or member 14 of the hasp and in operative engagement with the back of the said spring-member or plate 21, the latter being provided with a narrow portion, as 23, 40 snugly fitted between the surrounding flange-portions 20 of the lock-stud or lug 19, substantially as shown, and whereby the said spring-plate is held against displacement from its operative engagement with the 45 previously mentioned cam-member 22.

The operation of the catch will readily be understood from an inspection of the several figures of the drawings, and any further description of the same is therefore deemed unnecessary, suffice it to say, however, that when the lock-stud or lug 19 has entered into its retaining engagement with the receiving slot 9 in the wall 8 of the lower box-like element or shell 3, the laterally extending flange-portions 18 of the upper box-like element or shell 4 will act as stops, resting securely upon the said wall 8, so that the two elements 3 and 4 are thereby in perfect alinement to permit the spring-controlled hasp to be lowered down upon and

over the said lower box-like element or shell 3 and thereby provide for a perfect locking or holding relation of the main separable members of the catch, as will be clearly evident.

From the foregoing description of the present invention it will be clearly evident that I have devised a simply constructed and neat catch, in which the parts are easily and quickly assembled, and in which the usual hinge-ears and pintles are entirely dispensed with, and a device is made which can be more readily and cheaply manufactured, and is not likely to get out of order.

Of course I am aware that changes may be made in the general arrangements and combinations of the several devices and parts, as well as in the details of the construction of the said parts, without departing from the scope of the invention as set forth in the foregoing specification and as defined in the clauses of the claim which are appended thereto. Hence, I do not limit my present invention to the exact arrangements and combinations of the several devices and parts as described in the said specification, nor do I confine myself to the exact details of the construction of the said parts as illustrated in the accompanying drawings.

I claim:—

1. A catch comprising an upper and a lower element, said elements being surrounded by rearwardly extending flanges, one of the flanges of the lower element being provided with a lock-stud receiving slot, and a lock-stud projecting marginally from the lower rearwardly extending flange of said upper element, said lock-stud being adapted to enter said slot, and said lock-stud being provided with a rearwardly extending marginal flange, a spring-plate within the chambered portion of said upper element, said spring-plate being provided with a narrow extension fitted into the chamber portion of said lock-stud, and a hasp pivotally connected with said upper element, said hasp being provided with a cam-member in engagement with said spring-plate.

2. A catch comprising an upper and a lower element, said elements being surrounded by rearwardly extending flanges, one of the flanges of the lower element being provided with a lock-stud receiving slot, and a lock-stud extending from said upper element, said lock-stud being adapted to enter said slot, and said lock-stud being provided with a rearwardly extending marginal flange, a spring-plate within the chambered portion of said upper element, said spring-plate being provided with a narrow extension fitted into the chambered portion of said lock-stud, a hasp pivotally connected with said upper element, said hasp being provided with a cam-member in engagement

with said spring-plate, and horn-shaped members extending from said upper element with which portions of the hasp are adapted to engage, so as to limit the closing movement of the hasp.

3. A catch comprising an upper and a lower element, said elements being surrounded by rearwardly extending flanges, one of the flanges of the lower element being provided with a lock-stud receiving slot, and a lock-stud extending from said upper element, said lock-stud being adapted to enter said slot, and said lock-stud being provided with a rearwardly extending marginal flange, a spring-plate within the chambered portion of said upper element, said spring-plate being provided with a narrow extension fitted into the chamber portion of said lock-stud, stop-flanges extending inwardly from the side-flanges of said upper element and located one at each side of said lock-stud, and a hasp pivotally connected with the upper element, said hasp being provided with a cam-member in engagement with said spring-plate.

4. A catch comprising an upper and a lower element, said elements being surrounded by rearwardly extending flanges, one of the flanges of the lower element being provided with a lock-stud receiving slot, and a lock-stud extending from said upper element, said lock-stud being adapted to enter said slot, and said lock-stud being provided with a rearwardly extending marginal flange, a spring-plate within the chambered portion of said upper element, said spring-plate being provided with a narrow extension fitted into the chambered portion of said lock-stud, stop-flanges extending inwardly from the side-flanges of said upper element and located one at each side of said lock-stud, a hasp pivotally connected with the upper element, said hasp being provided with a cam-member in engagement with said spring-plate, and horn-shaped members extending from said upper element with which portions of the hasp are adapted to engage, so as to limit the closing movement of the hasp.

5. A catch comprising an upper and a lower element, said elements being surrounded by rearwardly extending flanges, one of the flanges of the lower element being provided with a lock-stud receiving slot, the side-flanges of said upper element having slotted portions providing bearings, and a lock-stud projecting marginally from the lower rearwardly extending flange of said upper element, said lock-stud being adapted to enter said slot, and said lock-stud being provided with a rearwardly extending marginal flange, a spring-plate within the chambered portion of said upper element, said spring-plate being provided with a narrow

extension fitted into the chambered portion 65 of said lock-stud, and a hasp pivotally mounted in said bearings, said hasp being provided with a cam-member in engagement with said spring-plate.

6. A catch comprising an upper and a 70 lower element, said elements being surrounded by rearwardly extending flanges, one of the flanges of the lower element being provided with a lock-stud receiving slot, the side-flanges of said upper element having 75 slotted portions providing bearings, and a lock-stud extending from said upper element, said lock-stud being adapted to enter said slot, and said lock-stud being provided with a rearwardly extending marginal flange, a spring-plate within the chambered portion of said upper element, said spring-plate being provided with a narrow extension fitted into the chambered portion of 80 said lock-stud, a hasp pivotally mounted in said bearings, said hasp being provided with a cam-member in engagement with said spring-plate, and horn-shaped members extending from said upper element with which portions of the hasp are adapted to engage, 85 so as to limit the closing movement of the hasp.

7. A catch comprising an upper and a lower element, said elements being surrounded by rearwardly extending flanges, one of 95 the flanges of the lower element being provided with a lock-stud receiving slot, the side-flanges of said upper element having slotted portions provided bearings, and a lock-stud extending from said upper element, said lock-stud being adapted to enter said slot, and said lock-stud being provided with a rearwardly extending marginal flange, a spring-plate within the chambered portion of said upper element, said spring-plate being provided with a narrow extension fitted into the chambered portion of 100 said lock-stud, stop-flanges extending inwardly from the side-flanges of said upper element and located one at each side of said lock-stud, and a hasp pivotally mounted in 105 said bearings, said hasp being provided with a cam-member in engagement with said spring-plate.

8. A catch comprising an upper and a lower element, said elements being surrounded by rearwardly extending flanges, one of the flanges of the lower element being provided with a lock-stud receiving slot, the side-flanges of said upper element having 115 slotted portions providing bearings, and a lock-stud extending from said upper element, said lock-stud being adapted to enter said slot, and said lock-stud being provided with a rearwardly extending marginal flange, a spring-plate within the chambered portion of said upper element, said spring-plate being provided with a narrow extension 120

sion fitted into the chambered portion of said lock-stud, stop-flanges extending inwardly from the side-flanges of said upper element and located one at each side of said lock-stud, and a hasp pivotally mounted in said bearings, said hasp being provided with a cam-member in engagement with said spring-plate, and horn-shaped members extending from said upper element with which portions of the hasp are adapted to engage,

so as to limit the closing movement of the hasp.

In testimony, that I claim the invention set forth above I have hereunto set my hand this 29th day of March, 1923.

AUGUST GOERTZ.
